(57) **CLAIM**

The ornamental design for a pneumatic toy car, as shown and described.

DESCRIPTION

FIG. 1 is a front perspective view of a pneumatic toy car showing my new design;

FIG. 2 is a rear perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines shown are included for the purpose of illustrating the unclaimed portions of the toy car and forms no part of the claimed design.

1 Claim, 9 Drawing Sheets

FIG.1

FIG. 5

FIG. 9
